No. 831,575.

PATENTED SEPT. 25, 1906.

W. M. TAYLOR.
WINDOW SASH.
APPLICATION FILED JULY 8, 1905.

UNITED STATES PATENT OFFICE.

WILLIAM M. TAYLOR, OF WESTON, WEST VIRGINIA.

WINDOW-SASH.

No. 831,575.

Specification of Letters Patent.

Patented Sept. 25, 1906.

Application filed July 8, 1905. Serial No. 208,868.

To all whom it may concern:

Be it known that I, WILLIAM M. TAYLOR, a citizen of the United States, residing at Weston, in the county of Lewis and State of West Virginia, have invented a new and useful Window-Sash, of which the following is a specification.

This invention relates to window-sashes, and has for its object to provide a device of to the class embodying new and improved means for ventilating the room in which the window is located.

It is highly desirable to be able to ventilate a room both near the top and bottom and which is ordinarily accomplished by moving the upper sash slightly down from the top and the bottom sash slightly up from the bottom of a window.

It is an object of this invention to provide 20 means whereby an aperture may be opened at the top or bottom, or both, of a window and without necessitating the unlocking of the sashes and in such manner as to prevent rain from beating in to the opening.

25 A further object of the invention is to provide apertures at the top of the top sash and bottom of the bottom sash of a window in which are horizontally-pivoted closures and means for securing the closures in a closed 30 position.

With these and other objects in view, the present invention consists in the combination and arrangement of parts, as will be herein-after fully described, shown in the accompanying drawings, and particularly pointed out in the appended claim, it being understood that changes in the form, proportions, size, and minor details may be made without departing from the spirit or sacrificing any of 40 its advantages.

In the drawings, Figure 1 is a view in front elevation of a window embodying this invention. Fig. 2 is a vertical sectional view of a window embodying this invention and taken 45 on line 2 2 of Fig. 1.

Like characters of reference designate corresponding parts throughout both the views.

In its preferred embodiment the invention forming the subject-matter of this application comprises a window-casing 10, having the usual ledge 11 and top jamb 12. Within the

casing is vertically slidable in the usual manner the upper sash 13 and the lower sash 14. Adjacent the top of the upper sash an auxiliary cross-bar 15 is provided and which forms 55 the upper frame-piece for holding the pane 16. The frame-piece 15 is beveled along its upper edge with an outward decline 17, and in the aperture between the cross-bar 15 and the upper end cross-bar 18 of the frame is 60 pivoted at 19 and 20 the frame 21, having its lower bar 22 beveled, as at 23, to coöperate with the bevel 17 of the bar 15. The frame 21 is angularly movable in a vertical plane about the pivots 19 and 20 and may be filled 65 with a pane 24 of colored or clear glass or other material. To hold the frame 21 in a closed position, any ordinary and approved means may be applied and shown conventionally as a turn-button 25. 70

The lower sash is provided adjacent its bottom cross-bar 26 with an auxiliary cross-bar 27, between which is pivoted the frame 28 similar to the frame 21 and held by a like fastening, as the turn-button 29. With the 75 frames 21 and 28 in the position shown it is obvious that the room will be ventilated at both the top and near the bottom, and that owing to the tilt of the frames rain is not likely to enter the apertures, and that when 80 closed the beveled points of contact serve to exclude the weather.

Having thus described the invention, what is claimed is—

A ventilator comprising an upper and a 85 lower sash, each sash comprising side, upper and lower rails permanently connected to form a rigid frame, and an intermediate rail permanently secured to the side rails of each sash and extending transversely thereof, the 90 intermediate rail of the upper sash being disposed nearer to the upper rail of said sash than to the lower rail, and the intermediate rail of the lower sash being disposed nearer to the lower rail of said sash than to the upper rail, glass fixedly secured between the intermediate and lower rails of the upper sash and between the intermediate and upper rails of the lower sash, a panel pivoted within the upper sash between the intermediate and upper rails, a panel pivoted in the lower sash between the intermediate and lower rails, 95 100

said intermediate rails being beveled and said panels adapted to swing into contact, and form a tight connection with their adjacent intermediate rails, said panels normally aligning with the glass within their sashes, and means upon the sashes for securing the panels in closed position.

In testimony that I claim the foregoing as my own I have hereto affixed my signature in the presence of two witnesses.

WILLIAM M. TAYLOR.
